NOVELTY GLOVE

Robert Stanton, 140 Geary St., San Francisco, Calif.

Filed July 21, 1960, Ser. No. 61,462

Term of patent 14 years

(Cl. D3—11)

The figure on the drawing is a front view of a novelty glove showing my new design, the broken line illustration of a mating glove being shown only for illustrative purposes.

The back of the glove is conventionally plain.

I claim:

The ornamental design for a novelty glove, as shown and described.
